UNITED STATES PATENT OFFICE.

GEORGE E. BELCHER, OF STOUGHTON, MASSACHUSETTS.

LAST.

1,134,506.

Specification of Letters Patent. Patented Apr. 6, 1915.

Application filed February 18, 1914. Serial No. 319,813.

To all whom it may concern:

Be it known that I, GEORGE E. BELCHER, a citizen of the United States, residing at Stoughton, county of Norfolk, Commonwealth of Massachusetts, have invented certain new and useful Improvements in Lasts, of which the following is a specification.

This invention relates to transversely divided lasts, and particularly to a two part last in which the last parts move on each other with a bearing formed by a dividing cut.

My present invention involves certain improvements over the device of my prior Patent No. 535,315, granted March 5, 1895, to which reference is made as illustrating the particular type involved herein. The device of my prior patent while in the main satisfactory and an improvement over the earlier structures of the art, was nevertheless open to several objections, which my present invention overcomes, as will appear hereinafter.

It should be pointed out at the outset that one of the most difficult problems in lasts of this type has been in the adjustment of the last parts. If the last parts are drawn up so tightly as to "stick," the friction developed makes it difficult and sometimes impossible to "break down" the last so that the last often has to be taken apart and readjusted. This invariably resulted in the spoiling of the shoe on that last so that it had to be thrown away. Then, too, the last is usually thrown away so that the loss is really double. If on the other hand the last parts are not drawn up tightly enough a condition equally as bad is reached. When it is considered that the pressure and strain to which the last is subjected in some of the shoe operations as for example in the sole leveling machines, is often sufficient to split a last, it is obvious that any unnecessary play or looseness at the union will soon cause the last to break down. It will therefore be seen that this matter of adjustment is one of extreme importance. The adjustment must be perfect with no latitude for error either way.

It is therefore one of the objects of my present invention to provide a divided last in which a predetermined adjustment of the

last parts may be secured to a mathematical nicety and which adjustment when made will be practically permanent as far as any usual variations are concerned.

Another source of difficulty in lasts of this type has been in the tendency of the wood of the last to wear away at the pivot pin whenever slack developed, or to split under the excessively heavy pressure, to which the last is subjected during the shoe operations. As is well known, this pressure is in the main directed upon the heel part although a considerable amount falls on the last union itself. The spindle socket in which the jack spindle enters is usually protected by a metallic thimble having a closed lower end, but often the pressure is so great as to break this closed end through and split the last. Various expedients have been devised in the effort to prevent this splitting of the last, of which the insertion of a simple contact piece in the vicinity of the thimble has been the most effective. This contact piece has been located in any variety of positions relative to the spindle socket and has been of any number of different sizes and material. I have found however, that by positioning a simple wooden or fibrous plug below the spindle and in the direct vertical line of thrust of the spindle, very effective results may be had. The grain of the plug preferably runs longitudinally so as to present maximum resistance.

The construction and operation of my invention will be more fully disclosed in the specification which follows.

In the drawings forming a part of that specification I have shown as an illustrative embodiment, constructions which not only clearly illustrate the principles involved, but are in themselves forms proven satisfactory in practice and well adapted to the requirements of manufacture.

Throughout specification and drawings, like reference numerals are correspondingly applied and in these drawings: Figure 1 is a central longitudinal section through a last in accordance with my invention. Fig. 2 is a face view of the fore part detached. Fig. 3 is a vertical section through the heel part and a portion of the fore part. Figs. 4 and 5 are plan and end views respectively of the

link which connects the last parts, and Fig. 6 is a detail view of the plug which reinforces the spindle socket.

I have indicated at 1 and 2 the fore and 5 heel parts respectively of a so called divided last which parts are adapted to move on each other with a bearing formed by a curved dividing cut. The fore part 1 has a vertical kerf 3 and the heel part 2, a longitudinal bore 4 extending from end to end 10 thereof. The last union in the form shown consists of a link 5 pivoted at its forward end in the fore part by a transverse pin 6, and guided in the kerf 3. At its rear end 15 the link seats in the bore 4 terminating just forward of the pin socket 14 and is fixed in the heel part by some fastening such as an upwardly driven screw 7 which passes through and closely fits a round hole 8 in 20 the body of the link. Beyond the hole 8 the link end is formed as a double slot 9 in which is received the forward end of a key 10 for drawing up on the link. The key 10 is axially mounted in the bore 4 in a bearing 25 afforded by the washer 11 which is applied to the rear face of the heel part. At this end the key 10 is threaded as indicated at 12. Adjustment of the key with resultant drawing up on the link is effected by a 30 nut 13. The thimble 14 of the spindle socket is reinforced by a plug or dowel 15 inserted into the heel part through a vertical bore let thereinto directly beneath the 35 thimble. The plug or dowel 15 is usually of wood or some fibrous material and is held in place beneath the lower closed end of the thimble by a suitable rivet. If of wood, the grain of the plug preferably runs 40 lengthwise so as to present maximum resistance.

In assembling the last the link 5 is first pinned in the fore part by the pin 6. The key 10 is next connected with the rear end 45 of the link by means of the joint and the last parts are tightened up by rotating the nut 13 to draw up on the key and link. A hole is now drilled through last and link and the screw 7 is driven to hold the link 50 end firmly in the heel part. By my improved construction therefore the link end is located in the heel part forward of the jack socket and yet is capable of being drawn up with all desired accuracy and of 55 being fixed in place when the last is so drawn up. The heel structure is furthermore strengthened by the longitudinal grain of the plug 15 which supports the jack socket and receives the thrust of the bush- 60 ing.

I have indicated in dotted lines, Fig. 1, a slightly modified form in which the link is normally inclined upwardly and rearwardly instead of normally lying in a horizontal 65 plane. In this form the bore for the setting

up device and link passes through the thimble above its closed end instead of passing below it. This avoids weakening the heel part beneath the thimble and obviates the necessity of boring a hole through the reinforcing plug. 70

Various other modifications in the form, and arrangement of parts may obviously be made, all without departing from the spirit of my invention if within the limits of the 75 appended claims.

What I therefore claim and desire to secure by Letters Patent is:

1. In a divided last including fore and heel parts, a link pivotally connecting said 80 parts and terminating within the heel part and externally operable and detachable; means disposed beyond the plane of the last and connectible with said link for drawing up said last parts. 85

2. In a divided last including a fore part and a heel part having a spindle socket, a link pivotally connecting said parts, and terminating in the heel part forward of the spindle socket, said heel part having a longitudinal bore to receive an externally operable 90 device for drawing up on said link, and a reinforcing plug in said heel part transverse of said bore and in vertical line with said socket and effective with the link 95 to prevent splitting of the last.

3. A two part last comprising a fore part and a heel part having a spindle socket, a link pivotally connecting said parts and terminating forward of said heel socket and 100 means for drawing up on said link.

4. A two part last comprising a fore part and a heel part and a union pivotally connecting said parts, said heel part having a spindle socket, a removable member extending longitudinally of the heel part below 105 said socket and operatively connected with the union for drawing up on the same, and means projecting beyond the plane of the heel part and operable externally of the heel 110 part for actuating said member.

5. In a divided last including a fore part and a heel part, a union pivoted in the fore part, means fastening said union in the heel part and independent means operatively 115 connectible with said union and effectively disposed to draw up said union.

6. A two part last comprising a fore part and a heel part having a spindle socket, a union pivotally connecting said parts and terminating short of said socket, means operable externally of the heel part for drawing up on the union, and a wooden reinforcing plug inserted in said heel part beneath and in line with said spindle socket and effective 120 with the link to prevent splitting of the last, said plug having its grain disposed longitudinally of the plug. 125

7. In a divided last including a fore part and a heel part, a union pivoted in the fore 130

part and terminating within the heel part, means fastening the union in the heel part, and independent means detachably connectible with the union and arranged to be positively engaged therewith when it is desired to draw up the last parts and be disengaged and wholly removed from the last when said drawing up has been effected.

8. In a divided last including a fore part, 10 and a heel part, a union pivoted in the fore part and terminating within the heel part, means fixing the union in the heel part and independent means detachably connectible with the union and arranged to be positively engaged therewith when it is desired to draw up the last parts and to be disengaged from the union and wholly removed from the last when said drawing up has

been effected, said drawing up means having an operating portion disposed beyond the plane of the heel part when the union is engaged.

9. In a divided last including a fore part and a heel part, a union pivoted in the fore part and terminating within the heel part, a member having a detachable engagement with said union and fixing said union in the heel part and independent means detachably connectible with said union and effectively disposed to draw up said union. 30

In testimony whereof I affix my signature in presence of two witnesses.

GEORGE E. BELCHER.
